(57) **CLAIM**

The ornamental design for a bottle with straw lid, as shown and described.

DESCRIPTION

FIG. 1 is a top, perspective view of a new design for a bottle with straw lid.

FIG. 2 is a bottom, perspective view thereof.

FIG. 3 is a front elevation view thereof.

FIG. 4 is a rear elevation of view thereof.

FIG. 5 is a left side elevation view thereof.

FIG. 6 is right side elevation view thereof.

FIG. 7 is a top plan view thereof; and,

FIG. 8 is a bottom plan view thereof.

The broken lines in the drawings depict portions of the bottle with straw lid that form no part of the claimed design.

1 Claim, 7 Drawing Sheets
